Attorney

UNITED STATES PATENT OFFICE.

CLARENCE IRVIN STAGE, OF ROCKFORD, ILLINOIS.

HAND STAMP.

Application filed August 10, 1926. Serial No. 128,411.

My present invention pertains to hand stamps, and contemplates the provision of a peculiar and advantageous hand stamp characterized by an auxiliary thumb or finger piece which is connected with the major portion of the stamp and extends forwardly from said major portion at the point where the ordinary handle is joined to the stamp frame or body.

10 With the foregoing in mind, the invention in all its details will be fully understood from the following description and claims when the same are read in connection with the drawings, accompanying and forming 15 part of this specification, in which:—

Figure 1 is a perspective illustrative of a hand stamp constructed in accordance with the preferred embodiment of my invention.

20 Figure 2 is a fragmentary vertical section on a slightly enlarged scale showing the manner in which I prefer to connect the auxiliary thumb or finger piece with the body and the handle of the stand.

25 Figure 3 is an enlarged plan view of the auxiliary thumb or finger piece, per se.

Similar numerals of reference designate corresponding parts in all of the views of the drawing.

30 Within the purview of my invention, the hand stamp, generally speaking, may be of the ordinary construction or of any other well known construction or any other construction compatible with the purpose and 35 use of my invention. The stamp illustrated comprises a frame or body 1 which carries stamping elements 2, a handle 3, of wood or other appropriate material, superposed upon the body or frame 1 and extending upwardly.

40 from the center thereof, and a screw 4 having a head 5 disposed below the crown bar of the body or frame 1 and also having a shank extending upwardly through an aperture in said crown bar and embedded in 45 the handle 3, Figure 2.

My novel auxiliary thumb or finger piece is designated generally by 6. It is formed in one piece of sheet metal or other appropriate material and is preferably made up of a body dished at 7, and an arm 8 extending from the said body and having an aperture 9. The arrangement of the auxiliary thumb or finger piece 6 relative to the body 1 and the handle 3 is clearly brought out in Figures 1 and 2, and by reference to said figures it will be understood that the

arm 8 is interposed between the confronting portions of the body 1 and handle 3, and the aperture 9 in the arm 8 is arranged to receive the shank of the screw 4. By virtue 60 of this construction and relative arrangement it will be understood that when the handle 3 is tightened upon the screw 4, the arm 8 of the auxiliary thumb or finger piece will be strongly clamped and held against 65 casual movement between the lower end of the handle 3 and a washer 10 which surrounds the shank of the screw 4 and is superposed directly upon the crown bar of the body or frame 1. Manifestly, when held 70 against casual movement in the manner stated, the auxiliary thumb or finger piece 6 will extend forwardly from the base of the handle 3 and forwardly and laterally with respect to the body or frame 1, so that the auxiliary 75 thumb or finger piece 6 will serve the additional function of indicating means designed to apprise the user of the stamp when the stamp is correctly positioned for the printing of characters by the printing element 2.

It will be gathered from the foregoing 80 that my novel auxiliary thumb or finger piece arranged as stated relative to the body 1 and the handle 3 constitutes a forward projection on the hand stamp so disposed that pressure of the thumb on the piece 6 may be utilized to advantage in pressing the printing element or elements 2 on the surface to be stamped, and in this connection it will also be appreciated that the provision of the dish 7 in the auxiliary thumb or finger piece is calculated to seat a thumb or finger and in that way prevent slipping of the thumb or finger incident to use of the 85 stamp.

The character of the particular stamp shown and described is of no moment, my invention in its broad aspect consisting in the provision of a projection extending forwardly from any kind of hand stamp.

Specifically considered, my improvement is practically advantageous because of the facility with which the auxiliary thumb or finger piece 6 may be attached to a stamp of common type of which many are at present in use, and in this connection it will be noted that the thumb or finger piece 6 may be expeditiously and easily fastened to a hand stamp such as shown without the employment of skilled labor, and without the employment of tools of any character, it being simply necessary to turn the handle 3

off the screw 4, place the apertured arm 8 of the thumb or finger piece 6 on the shank of the screw 4 and then turn the handle 3 down upon the screw shank until the arm 8 of the auxiliary thumb or finger piece is strongly clamped between the lower end of the handle 3 and the top or prong bar of the stamp body 1.

It will also be understood that my improvement is extremely simple and inexpensive and does not in any measure render a hand stamp cumbersome.

I have specifically described the construction and relative arrangement of the parts embraced in the present and preferred embodiment of my invention in order to impart a full, clear, and exact understanding of the said embodiment. I do not desire, however, to be understood as limiting myself to the precise construction shown and described, my invention being defined by my appended claims within the scope of which structural changes may be made without departure from my invention.

Having thus described the invention, what I claim as new and desire to secure by Letters Patent is:—

1. In a hand stamp and in combination, a frame or body, a screw carried by the frame or body and having a shank extending upwardly therefrom, a handle extending up-

wardly relative to the frame or body and receiving the shank of the said screw, and an auxiliary thumb or finger piece having a dished body portion disposed in front of the frame or body and also having an apertured arm extending from said body portion and receiving the shank of the screw and arranged in interposed relation between the top of the body or frame and the lower end of the handle.

2. A hand stamp having a body and a handle extending upwardly from said body and also having an auxiliary thumb or finger piece connected with the body and the handle and extending forwardly from the body adjacent to the point at which the handle is joined to the body and disposed substantially at right angles to the longitudinal vertical plane of the body.

3. As a new article of manufacture, an auxiliary thumb or finger piece for application to and use in hand stamps, the said auxiliary thumb or finger piece being formed in one piece in general plate-like configuration and having a dished body or major portion and also having a reduced and apertured arm extending from said body or major portion.

In testimony whereof I affix my signature.

CLARENCE IRVIN STAGE.
